UNITED STATES PATENT OFFICE.

JEAN DIEM-BEUTLER, OF BRUGGEN, SWITZERLAND.

TULLE OR NET EMBROIDERY.

No. 824,100.

Specification of Letters Patent.

Patented June 26, 1906.

Application filed December 17, 1904. Serial No. 237,316.

To all whom it may concern:

Be it known that I, JEAN DIEM-BEUTLER, a citizen of the Swiss Republic, residing at Bruggen, near St. Gallen, Switzerland, have 5 invented certain new and useful Improvements in Tulle or Net Embroidery, of which the following is a specification.

This invention relates to improvements in tulle or net embroidery; and it consists in tracing patterns on plain or colored tulle by means of transparent or translucent pigment free from fatty constituents or in applying said pigment to suitable fabric which corresponds in its outlines with the pattern to be produced and is adapted to be sewed to the tulle. In both cases the tracing or pattern can be edged with ornamental embroidery or the like.

The invention is illustrated, by way of example, in the annexed drawing, which represents a corner of a tulle curtain.

The flower pattern *b* and the border pattern *c* are produced on the tulle background *a* by means of pigment free from fat, and

both patterns are edged with embroidered 25 outlines *d*.

The color of the pigment used for producing each pattern need not, of course, be uniform. Any desired number of different colors may be used to produce a pattern, according 30 to the subject or nature of the latter. This is also the case if fabric corresponding in its outlines with the pattern is sewed to the tulle and edged by means of embroidery.

I claim—

In embroidered network the construction comprising in combination a network background, a pattern formed with permanent transparent pigment free from fatty constituents, spread over parts of said network, and 40 embroidery on said network placed so as to form an edging to said pattern.

In witness whereof I have signed this specification in the presence of two witnesses.

JEAN DIEM-BEUTLER.
